UNITED STATES PATENT OFFICE.

FRANCIS H. BUZZACOTT, OF CHICAGO, ILLINOIS.

DESIGN FOR A RANGE-OVEN DOOR.

SPECIFICATION forming part of Design No. 34,416, dated April 23, 1901.

Application filed March 18, 1901. Serial No. 51,784. Term of patent 7 years.

To all whom it may concern:

Be it known that I, FRANCIS H. BUZZACOTT, a citizen of the United States, residing at Chicago, in the county of Cook and State of Illinois, have invented and produced a new and original Design for a Range-Oven Door, of which the following is a specification, reference being had to the accompanying drawings, forming part hereof.

10 Figure 1 is a view of the external side of a range-oven door of my new and original design; Fig. 2, an edge view of the door; Fig. 3, an internal face view of the same, and Fig. 4 a vertical sectional view taken as indicated

15 at line 4 of Fig. 3.

As shown in the drawings, the leading or material feature of my design consists in a flat rectangular plate A, having an external raised margin or peripheral portion α , pivots

α' at the lower corners of the door and projecting beyond the vertical edges of the door, locking-lugs α^2 at the vertical edges of the door near the upper portions thereof, and a depression α^3 at the upper central portion of the door, affording a grip for the hand.

Having described my invention, what I claim as new, and desire to secure by Letters Patent, is—

10 The design for a range-oven door, as herein shown and described.

20 In testimony whereof I have signed my name to this specification in the presence of two subscribing witnesses.

FRANCIS H. BUZZACOTT.
